DESIGN FOR A COMBINATION SHELF, BRACKETS, AND TOWEL HOLDER

Roy S. Sanford, Oakville, Conn., assignor to The
Autoyre Company, Incorporated, Oakville,
Conn., a corporation of Connecticut

Application December 23, 1940, Serial No. 97,562

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Combination Shelf, Brackets, and Towel Holder, of which the following is a specification, reference being had to the accompanying drawing, forming a part thereof.

Figure 1 is a perspective view of a combination shelf, brackets, and towel holder showing my new design; and

Fig. 2 is an end elevational view of Fig. 1.

The characterizing features of my new design are shown in full lines, and reside in the provision of a pair of brackets, each comprising a ver-

tical arm and a horizontal arm extending from the upper end thereof with a diagonal member extending between and secured to intermediate portions of said arms, and a bar of substantially U-shape extending between the brackets in a plane substantially normal to a plane through the diagonal members with the opposite legs of the U-shaped bar respectively secured to intermediate portions of the diagonal members, all as shown.

I claim:

The ornamental design for a combination shelf, brackets, and towel holder, substantially as shown and described.

ROY S. SANFORD.
